UNITED STATES PATENT OFFICE.

WILLIAM W. WILSON, OF DORCHESTER, MASSACHUSETTS.

COLUMN-MOLD.

1,109,810.

Specification of Letters Patent.

Patented Sept. 8, 1914.

Application filed December 16, 1910. Serial No. 597,650.

To all whom it may concern:

Be it known that I, WILLIAM W. WILSON, a citizen of the United States, and a resident of Dorchester, county of Suffolk, State of 5 Massachusetts, (whose post-office address is 23 Bentham road, Dorchester, Massachusetts,) have invented an Improvement in Column-Molds, of which the following description, in connection with the accompanying 10 drawings, is a specification, like letters on the drawings representing like parts.

This invention relates to monolithic column molds being more particularly intended to provide a superior form of mold which 15 can also be erected and dismantled at slight expense.

My invention will be best understood by reference to the following description when taken in connection with the accompanying 20 illustration of one specific embodiment thereof, while its scope will be more particularly pointed out in the appended claims.

In the drawings: Figure 1 is an elevation partly broken away showing a column mold embodying one form of the invention; Fig. 2 is a section in plan on the line 2—2 in Fig. 1; but on a larger scale; and Fig. 3 is a similar section on the line 3—3 in Fig. 1.

Referring to the drawings and to the embodiment of the invention there shown, I have illustrated one form of a column mold for molding a concrete or other similar monolithic column 1. In preparing a mold for a column of this kind, it is customary to 30 form the sides of the mold of longitudinally arranged matched molding boards or other suitable molding members 2. These are held in place by means of a number of cross bars or cleats which are arranged transversely at 35 intervals to overlie the molding boards, these cross bars being customarily arranged in sets of four, opposite pairs of which are held in place by bolts, this serving to clamp or bind the sides of the mold together and give rigidity to the structure.

It is necessary to use the cross bars at frequent intervals, and, each pair of bars having a pair of bolts, the labor of constructing the mold and particularly of erecting it forms a heavy item of expense in this type of construction. It is also difficult to make it of uniform rigidity and dimensions throughout its length.

Through the use of my invention I eliminate the necessity of bolts for each pair of

cross bars. This is secured by utilizing longitudinal strips which overlie ends of the cross bars so that when opposite strips are bolted together at two or three points all intervening cross bars are clamped in tightly 60 against the sides of the mold. This greatly reduces the labor required in erecting and dismantling the mold and provides a more rigid mold, uniform throughout its length. It also permits the use of cross bars of 65 smaller dimensions since the strain in the mold is lessened.

Referring to the drawings, I have shown the molding boards 2 provided on opposite sides of the mold with a series of cleats or 70 cross bars 3, herein of wood, although metal may be used if desired, the cross bars being arranged in double pairs, one pair for each two opposite sides of the mold and used in sufficient numbers to give the required 75 rigidity to the structure.

Herein seven such sets of cross bars, are utilized, each bar being nailed or otherwise attached to the sides of the molding boards. The opposite members of each pair are 80 drawn together to clamp the molding boards between them, by longitudinal strips, preferably, though not necessarily, in the form of angle irons 4 which extend lengthwise the column and overlie the ends of the cross 85 bars, the latter preferably projecting somewhat beyond the limits of the molding boards. The angle irons or other strips being placed over these projecting ends, the bolts 5 are then employed to clamp the irons 90 together at any appropriate points, preferably, however, near the top and bottom of the mold and at one or more intermediate points according to the dimensions of the mold. Herein the angle irons are bolted together at the top and bottom of the column and near the mid portion thereof, each angle iron being joined to the next adjacent one by three separate bolts which lie outside 95 of the mold boards 2. While the bolts might also pass through the projecting ends of the cross bars, preferably they are arranged intermediate the latter so that no one of the cross bars requires a hole to be bored in it.

The strips or angle irons may be drilled at 100 frequent intervals as represented so that the bolts may be inserted at any point required.

The described form of column mold can be erected and dismantled in less than half 110 the time than the molds heretofore used and

is not only less expensive to construct and maintain, but is more accurate, rigid and efficient.

While I have herein shown and described for purposes of illustration, one specific form of the invention, it is to be understood that extensive deviations may be made therefrom without departing from the spirit thereof.

10 Claims—

1. In a monolithic column mold the combination with longitudinally extending molding walls and cross bars arranged transversely at intervals on each side of the mold to overlie the molding boards and longitudinal strips overlying the cross bars, the strips on opposite sides of the mold being bolted together at a plurality of points intermediate the cross bars to bind together 20 all the intervening cross bars.

2. In a monolithic column mold the combination with longitudinally extending molding walls of cross bars arranged transversely at intervals at each side of the mold 25 to overlie the molding walls and having their ends projecting beyond the sides of the mold, longitudinal metallic strips overlying the projecting ends of the cross bars, and connecting the strips on opposite sides 30 of the mold and disposed in said intervals at a plurality of points in the height of the mold to bind together all the intervening cross bars.

3. In a monolithic column mold the combination with longitudinally extending mold members, cross bars arranged transversely at intervals on each side of the mold to overlie the mold members and having their ends projecting beyond the sides of 40 the mold, and longitudinally extending angle irons having their sides extending from their intersection inwardly toward the middle of the corresponding face of the mold

and overlying the projecting ends of the cross bars, the opposed angle irons being 45 bolted together to clamp together the intervening cross bars.

4. In a monolithic column mold the combination with longitudinally extending mold members of cross bars arranged transversely at intervals on each side of the mold to overlie the mold members, longitudinally extending angle irons having their flanges extending inwardly toward each other on the adjacent face of the mold and overlying 55 the ends of the cross bars and bolts disposed in said intervals and clamping adjacent angle irons together, the bolts passing outside of the molding members.

5. In a monolithic column mold, the combination with longitudinally extending mold members, cross bars arranged transversely at intervals on each side of the mold to overlie the mold members, such cross bars consisting of pairs of oppositely disposed 65 members, and successive pairs being arranged in different planes and disposed substantially at right angles to the next pair and with their ends projecting beyond the sides of the mold, longitudinally extending 70 angle irons having their sides overlying the projecting ends of the cross bars to hold the same in position against the longitudinally extending mold members, and bolts disposed in said intervals and clamping each angle 75 iron to the adjacent angle iron whereby the said cross bars may be drawn tightly against the longitudinal mold members and the same clamped into a unitary structure.

In testimony whereof, I have signed my 80 name to this specification, in the presence of two subscribing witnesses.

WILLIAM W. WILSON.
